UNITED STATES PATENT OFFICE.

EVERT LAUTENBACH, OF CHICAGO, ILLINOIS.

RULE.

SPECIFICATION forming part of Letters Patent No. 687,762, dated December 3, 1901.

Application filed February 26, 1901. Serial No. 48,896. (No model.)

To all whom it may concern:

Be it known that I, EVERETT LAUTENBACH, a citizen of the United States, residing at Chicago, in the county of Cook and State of Illinois, have invented certain new and useful Improvements in Rules or Measures; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in rules; and it consists in providing a rule or measure, particularly an ordinary carpenter's rule, with a rigid strip pivoted at one end in one arm of the rule and adapted to engage its 20 free end in indentations in the other arm of the rule, whereby the parts may be set at different angles, particularly at ninety degrees to form a square or at forty-five degrees to form a miter.

25 Referring to the drawings, Figure 1 shows a carpenter's rule provided with my improvement set at an angle of ninety degrees and in dotted lines as set at an angle of forty-five degrees. Fig. 2 is a view of the inner edge 30 of the rule with the connecting-strip in closed position. Fig. 3 is a perspective of the strip detached, and Fig. 4 is a cross-section of the same.

The arms 5 and 6, pivoted at 7, represent 35 the rule. A metal strip 8, having a flange 9, is pivoted at one end by a pin 10 in a slot 12 in the inner edge of one arm of the rule, which slot is adapted to receive the strip when in closed position. In the other arm of the rule 40 are indentations or recesses 13 and 14, adapted to receive the free end of the strip 8 and set the arms at angles of ninety degrees and forty-five degrees, respectively.

The flange 9 is preferably of the same width 45 and thickness as the brass binding commonly

used on such rules, and the binding is cut away or a depression made in the rule, as at 11, so that when the strip is closed or seated in the slot 12 the flange is flush with the edge of the rule and the continuity of the straight- 50 edge preserved.

By the construction indicated the ordinary use of the rule in ruling and measuring is not interfered with, nor its appearance materially changed, which is an advantage over those 55 rules designed for the same purpose in which the connecting or adjusting arm when not in use projects or causes a surface irregularity, which interferes with the general use of the rule.

The strip 8 and flange 9 form a rigid connection or support, which will not buckle or yield to the ordinary pressure in ruling along the edge of the rule, as is apt to occur with rules having a spring or flexible connection 65 between the arms. My invention permits of easy and certain adjustment in its designed use, and when not in use is out of the way and in no manner interferes with any other use of the rule.

Having thus described my invention, what I claim as new, and desire to secure by Letters Patent, is—

1. A jointed rule having pivoted to one arm a flanged strip adapted, when closed, to enter a depression in the arm to which it is pivoted and form a flush surface therewith, and adapted when open to engage at its free end indentations in the other arm of the rule. 75

2. A jointed rule having pivoted to one arm 80 the strip 8 having the flange 9, a depression in the arm adapted to receive the strip and flange, and indentations in the other arm adapted to engage the end of the strip.

In testimony whereof I affix my signature 85 in presence of two witnesses.

EVERT LAUTENBACH.
